UNITED STATES PATENT OFFICE.

CLARENCE B. HARBISON, OF LIMA, OHIO, ASSIGNOR TO THE OHIO STEEL FOUNDRY COMPANY, OF LIMA, OHIO, A CORPORATION OF OHIO.

LOCOMOTIVE FRAME.

Application filed September 19, 1927. Serial No. 220,849.

This invention relates to improvements in locomotive beds or frames, and has for its object to provide a new and improved construction wherein the frame is cast in one 5 piece with a novel form of side girders or beams extending longitudinally thereof, and affording an improved arrangement for the spring equalizer rigging.

The invention may best be understood by 10 reference to the accompanying drawings, in which:

Figure 1 is a side view of a locomotive frame constructed in accordance with my invention.

15 Figure 2 is a plan view showing half of the frame, the other half, of course, being similar.

Figure 3 is an enlarged detail plan view of a portion of the frame shown in Figure 2.

20 Figure 4 is an enlarged detail side view of a portion of the frame shown in Figure 1.

Figure 5 is a transverse section taken on line 5—5 of Figure 2.

Figure 6 is a transverse section taken on 25 broken line 6—6 of Figure 2.

Figure 7 is a detail transverse section taken on broken line 7—7 of Figure 2.

Referring now to details shown in the drawings, it will be seen that I employ two 30 continuous girders 10—10 spaced symmetrically on each side of the longitudinal center of the locomotive. These girders are generally box-like in cross section, as clearly shown in Figures 5, 6 and 7, and each comprising outer walls 11—11 and inner walls 35 12—12. The girders are provided further with recesses 13—13 opening downwardly as usual and forming the pedestals for the driving axles, in the form shown four such pedestal openings being provided.

The two girders 10—10 are connected by suitable braces cast integral therewith, in the form shown these braces including a rear 40 end sill 14, front end sill or bumper 15 and a series of intermediate braces 16—16. These latter braces consist generally of upright webs having horizontally disposed flanges 16^a—16^b as is best shown in Figures 3 and 4. These cross braces, of course, may vary widely in construction and arrangement from that shown herein, depending on the design of each locomotive.

45 The journal boxes for the axles are mounted for vertical movement on the pedestals 13—13, and are engaged with spring saddles

17, 17 at their top for connection with the usual spring equalizing rigging.

In my improved construction, a series of openings 20 are provided centrally of the upper wall of pedestal openings 13—13, these 50 openings permitting the spring saddles 17 to extend therethrough and into the hollow portion of the girder 10 above each of said pedestal openings 13 where they are engaged with the spring equalizing rigging of any suitable 55 form. One form of equalizing rigging is indicated in dotted lines in Figure 1, from which it will be seen that the springs and equalizer bars are disposed above and between the hollow girders 10—10, the equalizer bars 70 having fulcrum bearings 22 in brackets 21—21. However, for convenience in illustration the spring rigging and journal boxes are omitted in the detail Figures 3 to 7, inclusive, so that the latter may clearly illustrate 75 the novel form and arrangement of the main frame itself, which forms the principal feature of my invention, it being understood that it is not the intention to limit the invention to any specific form of spring equalizing rigging.

In the form shown, it will be observed that the rear driver spring may be mounted within the side girder 10 while the three front springs may project above said girders 85 through openings 23—23 formed in the upper wall of said girders. In order to strengthen the girders adjacent these openings 23—23, I provide cross braces 24—24 between the inner and outer walls 12 and 11, 90 as clearly shown in Figures 3, 4 and 5. Strengthening flanges 25—25, projecting inwardly from the inner wall 12, may also be provided opposite the openings 20 to aid in strengthening the frame at this point. 95

With the construction above described, it will be observed that the spring saddles and hangers are mounted and guided between the upright walls 11 and 12 of the girder 10 instead of straddling the main girder of the 100 frame as in ordinary constructions. This construction affords an especially light and rigid structure for the main frame wherein the two side girders of approximately box section are arranged longitudinally substantially in line with the center line of the driving box journals. Furthermore, the two girders are properly braced to provide sufficient strength so that in service one frame 105 will be restrained from preceding the other 110

due to cylinder thrust, and to provide against distortion due to curving of the engine.

It will be obvious that the locomotive bed may also have other parts such as brackets, 5 guide yokes, brake fulcrum, etc., cast integrally therewith, if desired.

While I have illustrated and described the particular embodiment of my invention, it will be understood that I do not wish to be 10 limited to the exact construction shown and described, but that various changes and modifications may be made without departing from the spirit and scope of my invention.

I claim:

- 15 1. A locomotive bed formed of a single piece casting and including a pair of hollow longitudinal girders and cross braces connecting them together, each of said girders being of box-like structure including top, bottom and side walls, and having pedestals formed along the bottom thereof and pro-

vided with apertures in the bottom wall above said pedestal openings affording the extension of spring rigging into said girder, and reinforcing webs extending from one side 25 wall to the other above said apertures.

2. A locomotive bed formed of a single piece casting and including a pair of hollow longitudinal girders and cross braces connecting them together, each of said girders 30 being of box-like structure including top, bottom and side walls, and having pedestals formed along the bottom thereof and provided with apertures in the bottom wall above said pedestal openings affording the extension of spring rigging into said girder, and reinforcing webs extending from one side wall to the other above and in front and rear of said apertures to permit the spring saddle to pass therebetween.

Signed at Lima, this 15th day of Sept. 1927.

CLARENCE B. HARBISON.
